UNITED STATES PATENT OFFICE

105,053

DESIGN FOR A RAIL VEHICLE

Robert J. Burrows and Alfred O. Williams, Battle Creek, Mich., assignors to Clark Equipment Company, Buchanan, Mich., a corporation of Michigan

Application October 2, 1936, Serial No. 65,135

Term of patent 14 years

To all whom it may concern:

Be it known that we, Robert J. Burrows and Alfred O. Williams, citizens of the United States, residing at Battle Creek, in the county of Calhoun and State of Michigan, have invented a certain new, original, and ornamental Design for a Rail Vehicle, of which the following is a specification, reference being had to the accompanying drawings forming a part hereof:

In the drawings:

Figure 1 is an elevational view of one side of the vehicle shown in Figure 1;

Figure 2 is an elevational view of the opposite side thereof;

Figure 3 is a front elevational view of a rail vehicle showing the new design; and

Figure 4 is a rear elevational view of the vehicle shown in Figure 1.

We claim:

The ornamental design for a rail vehicle, as shown.

ROBERT J. BURROWS.
ALFRED O. WILLIAMS.
